UNITED STATES PATENT OFFICE.

WINFIELD S. HOLDEN AND AUGUSTUS D. HOLDEN, OF COVINGTON,
KENTUCKY.

LOCK-COCK.

SPECIFICATION forming part of Letters Patent No. 244,130, dated July 12, 1881.

Application filed June 6, 1881. (No model.)

To all whom it may concern:

Be it known that we, WINFIELD S. HOLDEN and AUGUSTUS D. HOLDEN, citizens of the United States, residing at Covington, in the county of Kenton and State of Kentucky, have invented certain new and useful Improvements in Lock-Cocks, of which the following is a specification.

Our invention relates to improvements on that class of lock-cocks shown in Patent No. 211,400, wherein is employed a detachable collar provided with a central angular perforation, through which the angular valve-stem passes, said collar having means for securing it in place by a padlock.

The object of the present invention is to provide a lock-faucet in which a cap-piece not only serves to lock the plug and to entirely cover and conceal the upper end of the plug and its stem, but which also serves to operate the valve or plug when detached.

To this end our invention consists, essentially, in the combination, with the valve or plug having an angular stem which terminates substantially on a line with the upper edge of the inclosing-barrel of the faucet, of a reversible combined cap-piece and wrench, having on its opposite faces means to engage the angular valve-stem, and serving to entirely cover and conceal the upper portions of said barrel and the valve or plug and its stem, said cap-piece also having means for securing it in place by a padlock. When the cap-piece is in its locked position one of its faces is in engagement with the valve-stem, and when the cap-piece is unlocked it can be reversed and its opposite face caused to engage said valve-stem, thereby serving as a wrench to operate the valve or plug.

In the accompanying drawings, Figure 1 represents a perspective view of a lock-cock constructed according to my invention and applied to the stave of a barrel; Fig. 2, a partially longitudinal sectional view thereof; Fig. 3, a plan of the inside of the cap-piece and wrench; Fig. 4, a plan of the barrel of the cock; Figs. 5, 6, and 7, detached views of parts which will be fully hereinafter explained.

A represents the stave of a cask which is to contain the liquid to be drawn off by the cock.

B represents the barrel of the cock; B', the

cylinder in which the valve or plug fits and turns in opening or closing the cock.

E represents the valve or plug; e', the port.

e represents the valve-stem, which is shown as made square, so as to allow a socket-wrench to be applied to turn the valve.

C represents a cap fitting the top or open end of the cylinder.

D' represents a socket rigidly attached, and forming a part of the cap C, and fitting on the end of the valve-stem e.

d represents a socket on the top of the cap, adapted to fit the valve-stem e, which cap and socket form a wrench with which to turn valve E.

c represent handles or lugs attached to the cap C.

c' represents an ear or lug projecting out on one side of the cap, fitting a corresponding lug, b, on the cylinder of the cock. Through these lugs a hole is pierced, so as to receive the hasp of the padlock to lock the cap in position. The lug b may be under one of the handles C, as shown in Fig. 5. Fig. 7 shows the cap in position to be used as a wrench to turn the valve.

d' represents a lug on the cap opposite the lock, and entering a hole, d'', tapped in the cylinder, so as to prevent the cap from being turned. It is obvious that this lug may be of any shape to fit a corresponding hole or recess in the cylinder.

I represents a lock-nut fitting the male thread cut on the end of the cock B.

I' represents a pin which enters a hole cut partly in the threads of tap I and partly in the threads on the cock, so that when the pin is inserted therein the nut is locked and the cock cannot be unscrewed from the outside.

i i represent a series of holes in tap I, so that the pin can be inserted without turning the tap I clear around.

The handles c can be omitted and the socket d form the cap, and a common wrench used to turn the valve, and still the cap and locking device would be embraced in the first two clauses of claims herein. So, also, the mode of applying the padlock can be variously modified without departing from the invention herein specified.

This lock-cock is especially adapted for use

on a whisky-tub to prevent the unlawful removal of spirits; but it is evident that there are various other vessels where its use will be of great utility.

5 We claim—

1. In a lock-faucet, the combining, with the valve or plug having an angular stem, terminating substantially on a line with the upper edge of the faucet-barrel, of a reversible combined cap-piece and wrench, having its opposite faces constructed to engage the angular valve-stem, and serving to entirely cover and conceal the upper portions of the barrel and the valve-plug and its stem, said cap-piece having means for securing it in place by a padlock, all substantially as and for the purpose described.
- 15 2. The combination of the faucet-barrel B', having the lateral perforation d'' and perforated lug b, the valve or plug E, having an an-

gular stem, e, terminating substantially on a line with the upper edge of the barrel, and the reversible combined cap-piece and wrench C, having an operating-handle, c, angular recesses in its opposite faces, and provided at 25 one edge with the perforated lug c' and on its under side with the lug d', said cap-piece serving to entirely cover and conceal the upper ends of the faucet-barrel and the valve or plug and its stem, all substantially as and for the 30 purpose described.

In testimony whereof we have hereunto set our hands in the presence of two subscribing witnesses.

WINFIELD S. HOLDEN.
AUGUSTUS D. HOLDEN.
